US00D651140S

(12) **United States Design Patent**
Greger et al.

(10) **Patent No.:** **US D651,140 S**
(45) **Date of Patent:** **** Dec. 27, 2011**

(54) **STROLLER FRAME TUBING**

(75) Inventors: **Jeff G. Greger**, Lititz, PA (US); **Michael L. Longenecker**, Lancaster, PA (US)

(73) Assignee: **Artsana USA, Inc.**, Lancaster, PA (US)

(**) Term: **14 Years**

(21) Appl. No.: **29/381,489**

(22) Filed: **Dec. 20, 2010**

(51) LOC (9) Cl. **12-12**

(52) U.S. Cl. **D12/133**

(58) **Field of Classification Search** D12/128-133;
280/62, 647-650, 29, 200, 47.38, 250.1,
280/259, 642, 658; 296/65.03, 65.04; 224/409;
297/DIG. 4

See application file for complete search history.

(57) **CLAIM**

The ornamental design for stroller frame tubing, as shown and described.

DESCRIPTION

FIG. 1 is a perspective view of a stroller frame tubing, showing our new design;

FIG. 2 is a perspective view of the fragmentary section taken from lines 2-2 in FIG. 1;

FIG. 3 is front elevation view thereof;

FIG. 4 is a left side elevation view thereof;

FIG. 5 is a right side elevation view thereof;

FIG. 6 is a rear elevation view thereof;

FIG. 7 is a top plan view thereof; and,

FIG. 8 is a bottom plan view thereof.

The broken lines illustrated environmental structure and form no part of the claimed design.

1 Claim, 7 Drawing Sheets
